UNITED STATES PATENT OFFICE.

SAMUEL M. NEELY, OF SMITH'S TURN OUT, SOUTH CAROLINA.

CYLINDER PLOW AND PULVERIZER.

SPECIFICATION forming part of Letters Patent No. 332,421, dated December 15, 1885.

Application filed May 8, 1885. Serial No. 164,829. (No model.)

To all whom it may concern:

Be it known that I, SAMUEL M. NEELY, of 5
Smith's Turn Out, in the county of York and
State of South Carolina, have invented a new
and useful Improvement in Cylinder Plows
and Pulverizers, of which the following is a
full, clear, and exact description.

Reference is to be had to the accompanying
drawings, forming a part of this specification,
10 in which similar letters of reference indicate
corresponding parts in all the figures.

Figure 1 is a plan view of one of my im-
proved plows and pulverizers. Fig. 2 is a
15 sectional side elevation of the same, taken
through the line *x x*, Fig. 1. Fig. 3 is a sec-
tional front elevation of the same, parts being
broken away. Fig. 4 is a rear elevation of one
20 of the tooth-bars partly in section. Fig. 5 is
a sectional end elevation of the same, taken
through the line *y y*, Fig. 4.

The object of this invention is to provide
cylinder plows and pulverizers constructed in
such a manner that they can be readily ad-
justed to work at any desired depth in the
25 ground, and to pulverize the soil to any de-
sired fineness, and which will automatically
clear the teeth of soil.

The invention consists in the construction
and combination of various parts of the cyl-
inder plow and pulverizer, as will be herein-
30 after fully described, and then pointed out in
the claims.

A are the wheels, the short axles B of which
are attached to the lower ends of two upright
35 bars, C. The upright bars C are connected
at their upper ends by a cross-bar, D, forming
the carriage-frame.

E is the plow-frame, to the middle part of
the side bars of which is rigidly attached the
40 shaft F. The ends of the shaft F project be-
yond the side bars of the frame E and enter
and slide up and down in vertical grooves in
the inner sides of the upright bars C. To the
45 middle parts of the side bars of the frame E
are attached the lower ends of chains G, which
pass up through holes in the cross-bar D, and
are attached to the grooved cams or roller-
segments H, rigidly secured to the ends of a
50 shaft, I. The shaft I rocks in bearings at-
tached to the cross-bar D, and to one of the
segments H is attached, or upon it is formed,
a lever, J, by means of which the said seg-

ments are turned to raise and lower the frame
E and its attachments. The lever J is pro-
vided with a spring-pawl, J', to engage with 55
a catch-bar, J'', attached to one of the bear-
ings for the shaft I and hold the said lever J,
and with it the frame E, in any position into
which they may be adjusted. To the center of
the front cross-bar of the frame E is attached 60
the tongue K, to which the draft is applied. To
the forward ends of the side bars of the frame
E are attached the forward ends of chains L,
the rear ends of which are attached to the
lower parts of the forward sides of the upright 65
bars C of the carriage-frame, so that the car-
riage will be drawn from the frame E. The
carriage-frame C D is held in an erect position
by the brace-bar M, the lower end of which is
70 attached to the rear end of the tongue K and
the front cross-bar of the frame E. The up-
per end of the brace-bar M is bent downward
into hook form, to hook into one or another of
the holes N, formed to receive it in the upper 75
side of the middle part of the top bar, D, so
that the said brace-bar can be adjusted as the
height at which the frame E is to be used may
require.

Upon the shaft F, at the inner sides of the
side bars of the frame E, are placed two disks, 80
O, which are connected and made to revolve
together by long bolts or rods P. In the in-
ner sides of the disks O, near their rims, are
formed annular grooves Q, to receive tenons
formed upon the ends of the bars R, to which 85
the teeth S are attached. At one or more
places in one or both disks O the part of the
rim of the said disk or disks between the
groove Q and the outer surface is cut away, as
shown in Fig. 3, so that the tooth-bars R can 90
be readily detached by slipping them around
to the said opening. The ends of the tooth-
bars R and the bottoms of the grooves Q are
roughened, as shown in Fig. 4, to prevent the
said tooth-bars from slipping, when arranged 95
in place and clamped between the disks O, by
screwing up the nuts of the long bolts P.

The teeth or plows S may be made of any
desired shape, as the character of the work to
be done may require, and their shanks are in-
serted in holes in the bars R, where they are
secured in place by pins T, passed through
holes in the said bar R and through recesses
in the shanks of the teeth S. Several recesses

are formed in the shanks of the teeth S to receive the pins T, so that the said teeth can be adjusted to project more or less, as may be desired.

5 Upon the shaft F, at the inner sides of the disks O, are placed eccentrics U, which are secured to the said shaft F by set-screws W, so that the said eccentrics will be held stationary.

10 Upon the eccentrics U are fitted annular disks X, which are connected by bolts or rods Y, and to which are hinged the ends of the arms of bails Z, the middle parts of which rest upon the teeth S, and which are pushed outward and drawn inward as the annular disks X are carried around the eccentrics U, by the revolution of the disks O. The disks O are made to carry the annular disks X with them, in their revolution, by a rod, f, which passes 15 through holes in the said annular disks X, and the ends of which enter radial grooves g in the inner sides of the said disks O, so that the said annular disks X will be free to adjust themselves to the eccentrics U while being carried 20 around by and with the said disks O. The eccentrics U are so arranged as to cause the bails Z to begin to move outward as the teeth S rise from the ground, so as to clear the said teeth of soil, or of grass, weeds, or other rubbish, and to be drawn inward as the said teeth 25 descend toward the ground, so as to be out of the way when the said teeth are working in the ground.

If desired, the clearers Z can be detached 30 and the teeth S kept clear by arms a, attached to the rear cross-bar of the frame E in such positions as to pass between the said teeth S as they rise, and thus clear the said teeth of rubbish. This modification is indicated in 35 dotted lines in Figs. 1 and 2. To the rear cross-bar of the frame E is attached the lower end of a standard, b, to the upper end of which is attached the driver's seat c.

If desired, the carriage A B C D can be 40 omitted and the machine used as a walking plow and pulverizer. In this case the standard b and seat c are omitted, and handles d are attached to the rear part of the frame E for guiding the machine, as indicated in dotted 45 lines in Figs. 1 and 2.

e are bars the lower ends of which are concaved to rest upon the ends of the stationary shaft F. The bars e are placed in the grooves in the inner sides of the uprights C of the 50 carriage-frame, and their upper ends project through apertures in the top bar, D, of the said frame, so that weights can be applied to the upper ends of the said bars e, to hold the

plow-frame E and its attachments down with any desired force, as the hardness of the ground 55 may require.

Having thus fully described my invention, I claim as new and desire to secure by Letters Patent—

1. In a cylinder plow and pulverizer, the 60 combination, with the frame E, of the stationary shaft F, the loose disks O, having annular grooves Q in the outer parts of their inner sides, the bolts P, connecting the disks, and the bars R, having end tenons to enter the 65 grooves of the disks O, and provided with teeth S and their fastening-pins T, substantially as herein shown and described, whereby the tooth-bars will be securely held and can be readily attached, adjusted, and detached, as set forth.

2. In a cylinder plow and pulverizer, the combination, with the frame E, the stationary shaft F, the grooved disks O, the tooth-bars R, and the teeth S, of the eccentrics U, 80 secured to the said stationary shaft F, the annular disks X, and the bails Z, hinged to the said annular disks X, substantially as herein shown and described, whereby the said bails will be pushed outward to clear the teeth 85 of rubbish as the said teeth rise from the ground, and drawn inward out of the way as the said teeth move downward, as set forth.

3. In a cylinder plow and pulverizer, the combination, with the plow-frame E and the 90 stationary shaft F, of the wheels and axles A B, the upright frame C D, having vertical grooves in the inner sides of its uprights to receive the ends of the said stationary shaft and the draft-chains L, and adjustable hook-brace M, connecting the said frames, substantially as herein shown and described, whereby the plow-frame is provided with a carriage, 95 as set forth.

4. In a cylinder plow and pulverizer, the 100 combination, with the plow-frame E, the stationary shaft F, attached to the said plow-frame, and the upright carriage-frame C D, having grooves in the inner sides of its uprights and apertures in its top bar of the 105 bars e, having concaved lower ends to rest on the said stationary shaft, substantially as herein shown and described, whereby weight can be applied to the said stationary shaft to hold the plow-frame and its attachments down with 110 any desired force, as set forth.

SAMUEL M. NEELY.
